UNITED STATES PATENT OFFICE.

ERNEST N. HUMPHREY, OF NEW BRITAIN, CONNECTICUT, ASSIGNOR TO TRAUT & HINE MANUFACTURING COMPANY, OF NEW BRITAIN, CONNECTICUT, A CORPORATION OF CONNECTICUT.

BUCKLE.

No. 880,216.

Specification of Letters Patent.

Patented Feb. 25, 1908.

Application filed July 1, 1907. Serial No. 381,617.

To all whom it may concern:

Be it known that I, ERNEST N. HUMPHREY, a citizen of the United States, residing at New Britain, in the county of Hartford and State of Connecticut, have invented certain new and useful Improvements in Buckles, of which the following is a specification.

My invention relates to improvements in buckles, and the objects of my improvement are simplicity and economy in construction, and convenience and efficiency in use, especially with reference to biting the web of a rustless buckle without having the said web change its position within the buckle, when the operating lever is turned down.

In the accompanying drawing:—Figure 1 is a front elevation of my buckle as applied to one end of a looped webbing. Fig. 2 is an enlarged vertical section of the same on the line $x-x$ of Fig. 4. Fig. 3 is a broken out side view of my buckle without the webbing. Fig. 4 is a plan view of the same. Fig. 5 is a front elevation of the same with the operating lever turned up into a position substantially at a right angle to the position shown in the preceding figures. Fig. 6 is a vertical section of the buckle and webbing on the line $x-x$ of Fig. 4, but with the webbing threaded differently from the threading in Figs. 1 and 2.

The frame or body of my buckle is in the form of a plate 7 with perforated ears or lugs 8 at each end, the said ears standing at about a right angle to the said plate. At the lower part of these ears I pivot the swinging jaw or plate 9 on the trunnions 10, with its biting edge 11 extended between the end ears or lugs 8 up nearly to the upper edge of the plate 7, which plate constitutes the other jaw of the buckle as well as the back of the frame. This other jaw and back of the frame is also between the end ears 8. The biting edge of the swinging jaw is bent or turned towards the rear and stands nearly at a right angle to the body of the said jaw. If desired the middle portion of this biting edge 11 may be cut away as shown at 12, Fig. 4 so that the said jaw bites mainly at its end portions.

The swinging jaw is forced towards its companion jaw and held in position when so forced, by means of an angle lever that is hinged or pivoted to the ears 8 and between the said ears by means of the trunnions 14.

When the webbing A is passed through the

buckle as shown in Fig. 2 the short arm 13 of the angle lever or operating lever bears on the front of the swinging jaw 9, while the longer arm 15 of the said angle lever serves as a handle for operating the said lever.

One end 16 of the webbing A is passed between the two jaws, that is in front of the plate 7 and in the rear of the swinging jaw 9 while the webbing extends downwardly so that it is doubled over the upper edge of the said plate 7. It may be left loose in this position or it may have the end 16 sewed or otherwise secured to the body or other thickness of the webbing as illustrated at 17 in Fig. 6. The webbing is then formed into a loop 18 and its opposite end passed upwardly between the two jaws in front of the end 16 as shown in Fig. 2. When so arranged one member of the loop 18 extends downwardly in the rear of the back, and the other member of the loop extends upwardly through the buckle between the said swinging jaw and the plate like jaw and back. When the lever handle 15 is forced downwardly as shown in Figs. 1 to 4 inclusive, the shorter arm 13 of the operating lever is firmly pressed against the front of the swinging jaw so as to cause the two jaws 7 and 9 to bite both thicknesses of the webbing and hold them with the buckle immovably fixed thereon with a given length of loop extending below the buckle. By throwing the lever handle 15 upwardly at a right angle to the position shown in Figs. 1 to 4, the pressure on the swinging jaw is released and the front thickness of webbing may be pulled through the jaws in either direction to shorten or lengthen the loop 18, as may be desired.

Instead of passing the second thickness of webbing upwardly between the two jaws as before described, it may be passed upwardly in front of the swinging jaw 9 and in rear of the shorter arm of the angle lever so that the said shorter arm acts directly on the webbing to hold it, as shown in Fig. 6. In either event the buckle is covered by the webbing so as to form what is called a rustless buckle. By means of the swinging jaw I am enabled to avoid the direct contact of the shorter arm of the operating lever with the webbing, whereby the webbing is less liable to be injured and there is no tendency to make the buckle crawl on the webbing during the closing or pinching movement of the lever. This prevention from crawling enables one to

more conveniently adjust the loop to the exact length desired.

I claim as my invention:—

1. A rustless buckle for a webbing, comprising a frame having a plate-like back with ears at its opposite ends, one jaw of the buckle being formed on the said back between the said end ears, and a free and unobstructed passage for the webbing over the said jaw of the back between the said ears, a swinging jaw pivotally mounted on the said ears and having a biting edge extended lengthwise of the said frame between the said end ears for coacting with the jaw portion of the said back, and an operating lever pivotally mounted on and between the said end ears of the frame with its shorter arm in position for acting upon the said swinging jaw near the biting edge thereof for pressing the jaws together, the said frame, jaws, and lever, being all combined and arranged with a free pas-

sage for the webbing to extend longitudinally wholly through the buckle between the said ears.

2. In a rustless buckle, the combination of a frame having a plate-like jaw and back, a swinging jaw mounted on the said frame and adapted to move to and from the said jaw and back, an operating lever mounted on the said frame for forcing the said swinging jaw towards the said jaw and back, and a webbing having one end secured to the said frame and a loop extending downwardly therefrom with one member of the loop in the rear of the said back, and the other member thereof extending upwardly through the buckle between the said swinging jaw and the said plate-like jaw and back.

ERNEST N. HUMPHREY.
